UNITED STATES PATENT OFFICE

JOHN J. CONNERS, OF TUCKAHOE, NEW YORK

DESIGN FOR A COMBINATION TABLE AND CABINET

Application filed March 23, 1931. Serial No. 39,201. Term of patent 3½ years.

To all whom it may concern:

Be it known that I, JOHN J. CONNERS, a citizen of the United States, residing at Tuckahoe, in the county of Westchester and State of New York, have invented a new, original, and ornamental Design for a Combination Table and Cabinet, of which the following is a specification, reference being had to the accompanying drawings, forming part thereof.

I claim:

The ornamental design for a combination table and cabinet substantially as shown.

JOHN J. CONNERS.
